HENRY KOCOUREK AND LOUIS AEBY, OF CHICAGO, ILLINOIS

CONNECTION AND VALVE FITTING FOR AUTOMOBILE WATER-CIRCULATING SYSTEMS

Application filed October 28, 1922. Serial No. 597,449.

The purpose of this invention is to provide an improved means for heating the cab of a motor vehicle by means of a circulatory system which is primarily provided for cooling the engine. It consists in the elements and features of construction shown and described, as indicated in the claim.

In the drawings:—

Figure 1 is a diagrammatic view showing the several parts of the system which constitutes this invention in their relation to each other and to the engine and cab.

Figure 2 is a horizontal section axial with respect to the water circulating pump and the intake pipe thereto as indicated at line 2—2 on Figure 1.

Figure 3 is a side elevation of the pump casing and bracket extension thereof for mounting it on the engine.

Figure 4 is a view looking in the direction of the arrow, 4, on Figure 3, being an end elevation of the pump with the inlet closure plate removed.

Figure 5 is a vertical section through a three-way valve which is interposed in the discharge pipe leading from the radiator to the heater at the junction with said pipe of a branch leading to the pump intake, axial with respect to said pipe and trans-axial with respect to the valve, showing the valve positioned for including the heater in the circuit with the radiator pump and engine jacket.

Figure 6 is a view similar to Figure 5 showing the valve positioned for cutting off flow to the heater and opening communication directly with the pump intake.

Figure 7 is a detail section at the line, 7—7, on Figure 6.

Figure 8 is an elevation of a member of a three-way valve device above mentioned.

In the structure shown in the drawings, the engine jacket, A, is shown connected directly with the discharge pump, B, and connected with the top of the radiator, C, by a pipe, 1. A discharge pipe, 2, leading from the bottom of the radiator, connects the latter with the intake D of the heater located in the cab, and from the heater, the pipe, 3, leads as seen at f, to the intake of the pump as seen at b¹. A three-way valve cas-

ing, F, is interposed in the pipe line, 2, between the radiator discharge and the heater intake, the third connection of said casing being with the pipe line, 3, as seen at f, leading to the pump intake. The pump is of the centrifugal type having its intake at the center of its casing, and having tangential discharge at the periphery as seen at b, into the engine jacket through the port, a; said pump casing being mounted against the engine jacket by means of the flange, 9, around the discharge port, which registers with the port, a, leading into the jacket cavity. The flange, 9, is a part of a bracket extension, 10, of the pump casing, said bracket extension having a journal bearing, 11, for the shaft, 8, of the pump rotor, 7, which extends out of the pump casing through a journal bearing, 12, provided with a stuffing box, 13. Said bracket extension, 10, has set through it a screw, 14, which is adapted to be set against the outer wall of the engine jacket, springing the bracket arm, 10, in slightly in order to align the journal bearings, 11 and 12. The bracket, 10, is held toward, and the screw, 14, against the engine body by the pump driving belt, 15, which passes about the pulley, 16, on the pump rotor shaft, 8.

It will be understood that at one position of the three-way valve, F¹, in the casing, F, shown in Figure 5, said valve affords communication directly from the discharge of the radiator to the intake of the heater, through the entire length of the pipe line, 2, so that there is a single circuit for the water, in which are contained both the radiator and the heater; and that at another position of said valve, F¹, shown in Figure 6, said valve cuts off communication through the pipe line, 2, between the radiator and the heater, and opens communication from the radiator to the pump intake; so that there is still only a single circuit, but this circuit does not include the heater, but only the radiator in connection with the pump and engine jacket. It will also be seen that the valve, F¹, may be set at an intermediate position at which it will only partly close the communication through the pipe line, 103

2, to the heater, and only partly open communication into the pipe, 3, so that the hot water withdrawn from the discharge of the radiator will partly pass said valve toward the heater, and through the heater and thence back through the pipe, 3, to the pump intake, and another part of the water will pass directly from the valve to the pipe, 3, and to the pump intake. The valve, F¹, has its stem provided with a lever handle, 18, for operating it, and this handle may, if desired, be provided with a connection extending into the cab so that the circulation may be controlled at the will of the occupant.

10 We claim:—

15 A fitting for the purpose indicated comprising two parallel water passages each open at both ends with a transverse water connection between them intermediate their ends, one of said passages having a cylindrical chamber disposed substantially at the point of intersection between the passage and the transverse connection, the axis of said chamber being transverse to the axis of the passage and the connection, whereby 20 the cylindrical wall of said chamber comprises three ports, together with a valve member in the form of a hollow cylinder having a portion of its cylindrical wall cut away, the remaining portion being sufficient 25 in extent to cover only one of said three ports at a time, and means for turning said valve member about the axis of the valve chamber, one of said parallel passages terminating in a connection flange for attachment 30 to a pump, the other end of said passage and the corresponding end of the other parallel passage being formed for connection with flexible tubing to communicate 35 with a heater coil or the like.

40 In testimony whereof, we have hereunto set our hands at Chicago, Illinois, this 26th day of October, 1922.

HENRY KOCOUREK.
LOUIS AEBY.
